United States Patent Office

Des. 180,355
Patented May 28, 1957

180,355

MOP

William M. Blackburn, Millbrae, Calif.

Application November 26, 1956, Serial No. 43,930

Term of patent 14 years

(Cl. D9—2)

Fig. 1 is a perspective view of a mop showing my new design.

Fig. 2 is a view of the mop in front elevation.

Fig. 3 is a view of the mop in side elevation.

I claim:

The ornamental design for a mop, as shown.
